Attorney

UNITED STATES PATENT OFFICE.

WILBUR L. WRIGHT, OF FULTON, NEW YORK, ASSIGNOR TO SEALRIGHT CO., INC., OF FULTON, NEW YORK, A CORPORATION OF NEW YORK.

INSULATING CONTAINER AND THE LIKE.

1,421,649.

Specification of Letters Patent. Patented July 4, 1922.

Application filed October 20, 1919. Serial No. 331,796.

To all whom it may concern:

Be it known that I, WILBUR L. WRIGHT, a citizen of the United States, and resident of Fulton, county of Oswego, State of New York, have invented certain new and useful Improvements in and Relating to Insulating Containers and the like, of which the following is a specification.

This invention relates to certain improvements in insulating containers and the like, and the objects and nature of the invention will be readily understood by those skilled in the art, in the light of the following explanation of the accompanying drawings illustrating what I now believe to be the preferred embodiment or mechanical expression of my invention from among other forms, constructions and arrangements within the spirit and scope thereof.

10 It is an object of the invention to provide a container for holding a receptacle such as a fruit jar, paper package, or the like, containing food-stuffs for example, with a minimum change of temperature in the receptacle while in storage or transportation.

20 A further object of the invention is to provide a container for this purpose, in which the receptacle placed therein will be spaced from the walls of the container to provide dead air spaces about the receptacle, with a minimum contacting surface between the container and the receptacle, thus materially reducing the transmission by induction of heat or cold from the receptacle to the container.

30 A still further object of the invention is to provide a container of simple and inexpensive construction, which preferably may be formed entirely of stiff paper adapted to be readily cut, and wound into tubing upon paper-working machines of standard or any preferred construction, thus providing a container which may be readily manufactured without the use of machinery other than that to be found in any plant given to the manufacture of paper articles.

40 With these and other objects in view, the invention consists in certain novel features in construction, and in combinations and arrangements as more fully and particularly set forth and specified hereinafter.

50 Referring to the accompanying drawings:

Fig. 1, is a vertical section through a package constructed in accordance with my invention, showing a receptacle, instanced as a glass jar contained therein.

55 Fig. 2, is a top plan view of the same with the cover of the package removed.

Fig. 3, is a perspective view of the various elements which when assembled go to form the package or container.

60 Fig. 4, is a similar view of the parts forming the cover for the package.

In the preferred form, I have shown the container as comprising an outer casing 1, instanced as formed of paper preferably shaped into a cylindrical tube by winding a strip 2 of the same upon a paper-tube winding machine.

70 The base of the casing is shown as a paper disk 3 received within the lower end of the cylinder, with the lower edge portion 4 thereof, crimped upon the downwardly bent outer edge portion 5 of the disk as shown at 6 in any preferred manner, as well understood in this art.

75 A false bottom is received within the casing, spaced from the base to form a dead air space 7 which acts as a heat insulating medium for the receptacle received within the container. This false bottom is shown as a paper disk 8, fitting snugly within the cylindrical tube, and instanced as resting upon a tube 9 supported upon base 3, thus spacing 80 the false bottom from the base. The tube 9 is preferably a strip of paper wound into cylindrical shape, and is shown as of substantially less diameter than cylinder 1, whereby it contacts with the false bottom 90 and the base of the container only at its upper and lower edges, thus reducing to a minimum the transmission of heat by induction from the false bottom to the outside of the container.

85 The receptacle supported within the container upon the false bottom, and shown in the drawings as a glass jar 10, although it will be obvious that any receptacle may be so carried, is preferably of substantially less cross-sectional area than the container so that when centrally positioned within the same, a dead air space 11 is formed between the side-walls of the container and the receptacle.

95 100 105 Means are provided for centrally dispos-

ing the receptacle within the container, so as to maintain this air space completely around the sides of the receptacle. I have shown these positioning means as comprising annular members 12, instanced as flat paper rings, fitting snugly within the casing of the container and secured in spaced relation therein, the rings preferably being of such width as to space the receptacle a substantial distance from the side walls of the container.

These rings and the false bottom of the container, may be held in position by spacing members 13 shown as fitting snugly against the inner surface of the side walls of the container, and disposed between adjacent rings, and between the upper and lower ring and the top and false bottom of the container respectively. The spacing members are preferably formed of strips of paper 14 wound into cylindrical tubes. The spacing member at the top of the casing above the upper ring is preferably of such width as to terminate short of the upper edge 25 of the casing, forming a shoulder 15 against which the lip of the closure for the container is adapted to abut as will be hereinafter described.

A closure having a dead air space formed therein is provided for the container. This closure is instanced as comprising a wound paper tube 16 having a disk 17 crimped over its upper end, as by having the edge 18 of the tube bent back and crimped upon the upwardly bent outer edge 19 of the disk, in a well known manner.

A false top is provided within the closure spaced from the end disk to form a dead air space 20. This false top is shown as a disk 21 fitting snugly within the closure and positioned between a spacing member shown as a wound paper tube 22 fitting within the closure, and received between the false top and the end disk; and a retaining member, exemplified as a wound paper tube 23, which fits snugly against the inner surface of the side walls of the closure below the false top.

The retaining member 23 may extend below the lower edge of the tubing forming the closure, to provide a lip 24, adapted to be received within the open end of the casing forming the container, this said lip resting upon the shoulder 15 formed for that purpose at the mouth of the container.

In assembling the container as thus described, the various parts may be glued together wherever necessary, and the entire container may, if desired, be treated with paraffine or other moisture proof substance.

In practice it will be found desirable to employ a container with an inner receptacle of less cross-sectional area than the openings in the annular members positioned upon the inner surface of the side walls of the container, so that the inner receptacle will only

contact with these annular members throughout a part of its circumference, thereby still further reducing the transmission of heat from the receptacle through the annular members.

For a similar reason, an inner receptacle is preferably employed which is of such height as to not contact with the false top of the closure for the container.

By the construction as thus described, it will be seen that I have provided a container for a receptacle, in which the inner receptacle is completely surrounded by dead air spaces forming heat insulators, the points of contact between the inner receptacle and the container being reduced to a minimum to prevent the transmission of heat by induction.

I have thus provided an inexpensive and efficient method for the storage and transportation of food-stuffs and the like, the temperature of which it is desired to maintain for some period of time.

While I have shown my improved container as of cylindrical shape and formed from paper tubing, it will be obvious that the shape and material of which the container is formed may be changed without departing from the spirit and scope of my invention, and hence I do not wish to limit myself to the exact disclosures hereof.

What I claim is:—

1. The combination with a storage receptacle, of a container therefor having false ends spaced from its outer ends and internal spacing members for positioning said receptacle out of contact with the walls of said container, said receptacle being of less height than the space between said false ends, and of less cross-sectional area than the space within said spacing members.

2. A container of the character described, comprising a casing having annular spacing members fitting therein against the side walls of the casing, and positioning means for said spacing members comprising annular members fitting within said casing between the spacing members.

3. A container of the character described, comprising a casing having annular spacing members fitting therein against the side walls of the casing and positioning means for said spacing members comprising annular members fitting within said casing between the spacing members, and between the ends of the casing and the spacing members.

4. A container of the character described, comprising a casing having false ends fitting therein in spaced relation from the outer ends of said casing, annular spacing members fitting in said casing against the side walls of the same, and positioning means for said spacing members and false ends, comprising annular members fitting

within said casing between the spacing members, and between said false ends and the spacing members, and between the false ends and the outer ends of said casing.

- 5 5. A container of the character described, comprising a casing forming a body and a closure therefor, said casing having annular spacing members fitting therein against the side walls of the same, and positioning 10 means for said spacing members comprising annular casings fitting within said outer casing between the spacing members, and between the ends of the outer casing and the spacing members, the junction between said 15 body and its closure in the outer casing being staggered with relation to said junction in the inner annular positioning casings.

6. A container of the character described, 20 formed of wound tubing end disks therefor, spacing rings fitting in said tubing, and positioning means for said rings comprising wound tubing fitting within said outer tubing between said rings, and between the end 25 disks and said rings.

7. A container of the character described, formed of tubing, end disks therefor, inner end disks fitting in said tubing in spaced 30 relation from the outer end disks, spacing rings fitting in said tubing, and positioning 35 means for said rings and inner end disks fitting within said outer tubing between said rings, and between said inner end disks and said rings, and between said inner end disks and the outer end disks.

8. An insulating container for removably receiving and enclosing a receptacle or other can, said container comprising a paper material body having a permanent end closure 40 providing an insulating end air space, the closure and the end of said body being crimped together to secure the closure and provide the container with an exterior rim, an exterior removable slip closure for the 45 opposite end of said body providing an insulating end air space and a depending flange to longitudinally telescope and cooperate with said body in forming an approximately air tight slip joint, the internal cross 50 sectional dimensions of said body substantially exceeding the corresponding dimensions of said receptacle to provide an insulating air space around the same, and means within the body to hold said receptacle approximately centrally within said 55 body and spaced from the inner surface thereof.

9. An insulating container to removably receive and enclose a can or other receptacle, 60 said container comprising a paper material barrel provided with a tight permanent bottom closure crimped to the lower end of the body and an interior fixed bottom head forming a base for the receptacle and spaced 65 from the closure to provide an intervening

insulating air space, and a removable insulating slip cover for the other end of the body having an annular depending flange so that the cover and body longitudinally telescope to form an approximately air tight 70 joint, said body having internal means to approximately center the receptacle therein and provide insulating air spaces around the same.

10. An insulating container for removably 75 receiving a can or other receptacle, comprising a body spanned at its lower end by a permanent tight closure, a can sustaining floor at its edge fitting the inner surface of the body and spaced upwardly from the closure, floor sustaining means between the closure and floor, an exterior removable insulating slip cover for the upper end of and longitudinally slid able on and from the body, and means within the body to provide 80 an insulating air space around the can when located in the body.

11. An insulating container for removably receiving and to serve as a carrier for a can or other receptacle having a top closure, 90 comprising a paper material barrel having an internal diameter substantially exceeding the external diameter of the can to provide a surrounding insulating air space the inner wall of which is formed by the can itself, 95 means being provided to contact the can and approximately center the same within the barrel, said barrel having insulating end closures one of which is formed by a removable cover, the interior length of the 100 container exceeding the exterior length of the removable can and its top closure.

12. An insulating container for removably receiving and to serve as a carrier for a can or other receptacle, comprising a paper 105 material barrel having an internal diameter substantially exceeding the external diameter of the can to provide a surrounding insulating air space the inner wall of which is formed by the can itself, said body having 110 a series of flat annular paper-material spacing rings radially projecting into said air space to approximately center the can, by minimum edgewise contact, and insulating end closures for the opposite ends of the 115 body, one of which is removable, means being provided within the container to establish insulating spaces beyond the upper and lower ends of the removable can within the container.

13. A paper material insulating container constructed and arranged to removably receive and constitute a carrier for a can or other receptacle that is provided with its own top closure, said container comprising a 125 barrel having an interior transverse can supporting floor and end closures, one of which forms a removable slip cover, the diameter of said body substantially exceeding the exterior dimensions of the can to provide an 130

- insulating air space around the can, means being provided for approximately centering the can within the body and reducing conducting contact therewith to the minimum, 5 means also being provided to establish insulating air spaces within the container below the removable can and above the top closure of said can.
14. An insulating container constructed 10 and arranged to removably receive and enclose a can and its cover and to reduce to the minimum exchange of temperature by radiation and conduction between the can and the exterior of the container, said container comprising a paper material tubular body provided with means to limit the lateral movement of the can within the body having minimum temperature conducting contact with the can and to establish an insulating 15 space within the body around the can, a bottom closure for the body, means within the body for upholding the can therein and establishing an insulating space between the can and said closure, and a removable top 20 closure for the body arranged a distance above the can cover, means being provided to

establish an insulating space within the container above the can cover.

15. An insulating container constructed and arranged to removably receive and enclose a can and its cover and to reduce to the minimum exchange of temperature by radiation and conduction between the can and the exterior of the container, said container comprising a paper material tubular body provided with means to limit the lateral movement of the can within the body having minimum temperature conducting contact with the can and to establish an insulating space within the body around the can, said container provided with a bottom support for the can and a paper material end wall closing the lower end of said body and establishing an insulating space between the can and said wall, a paper material end 40 wall closing the upper end of the container, and means establishing an insulating space above the can cover and below said last mentioned end wall, said container embodying a removable closure.

WILBUR L. WRIGHT.
